United States Patent Office

Des. 188,481

Patented Aug. 2, 1960

188,481

SOAP HOLDER

James L. Hvale, Chicago, and William F. Meará, Oak Park, Ill., assignors to Ekco Products Company, Chicago, Ill., a corporation of Illinois

Filed Jan. 8, 1960, Ser. No. 58,976

Term of patent 14 years

(Cl. D4—3)

Fig. 1 is a top plan view of a soap holder embodying our new design.

Fig. 2 is a bottom plan view thereof.

Fig. 3 is a front elevational view thereof.

Fig. 4 is a left side elevational view thereof.

Fig. 5 is a vertical cross-sectional view thereof taken on line 5—5 of Fig. 1.

We claim:

The ornamental design for a soap holder, as shown.
